UNITED STATES PATENT OFFICE.

CHARLES C. JESSEN, OF WILMINGTON, DELAWARE, ASSIGNOR TO ATLAS POWDER COMPANY, OF WILMINGTON, DELAWARE, A CORPORATION OF DELAWARE.

METHOD OF MANUFACTURE OF ARTIFICIAL SILK.

Application filed November 10, 1924. Serial No. 749,094.

This invention relates to a method of manufacture of artificial silk and more particularly to a manner of handling the same to prevent mechanical damage to the silk from handling in the several steps through which it passes.

In the manufacture of artificial silk, cellulose is reduced to a syrup like consistency by various methods. Among these are the 10 nitro-method, the viscose method, and the copper-ammonia method. In these several methods it becomes necessary to remove residual substances from the threads after the solution has been discharged from the 15 spinnerets and brought to thread-like form by its passage through a suitable solidifying or precipitating bath.

For purposes of clearness I will describe the invention as applied to the copper-ammonia method of manufacturing artificial silk, though, as will be hereinafter set forth, the invention is of utility in connection 20 with the other methods named.

In the manufacture of artificial silk by 25 the copper ammonia process, cellulose is reduced to a syrup like solution by the action of copper sulphate and ammonia. This solution is forced through the fine holes of spinnerets directly into an alkaline precipitating bath which instantly solidifies it to such an extent that it becomes a series 30 of well defined threads of such strength as to permit of their being handled in the subsequent operations. It is very necessary however, to remove from the threads, substantially all traces of the chemicals used 35 in bringing the cellulose into solution form. Some of the ammonia is removed in the alkaline precipitating bath and most of the 40 remainder of the ammonia is removed by evaporation in the subsequent operations.

The removal of the copper is not effected as easily as the removal of the highly volatile ammonia and, heretofore, the mechanical handling to which the silk was 45 subjected in the removal of the copper has resulted in considerable damage to the same with consequent waste and loss.

In the manufacture of artificial silk, there 50 are at present in general use, two methods of spinning. One is the so-called spool or bobbin spinning, and the other, pot spinning. In the first, or bobbin method, the individual and untwisted threads emerging 55 from the precipitating bath are collected on

rotating cylinders, spools or bobbins. The subsequent chemical treatments, washing and drying, are applied to the thread while it is on the cylinder or spool. After the thread is chemically in its final stage, the 60 thread is unreeled from the cylinder or spool, twisted and then skeined. This process causes a waste of material and labor because if one filament breaks, it is not picked up by the others, and causes tangling.

In the second, or pot method, the threads in parallel are passed into a rapidly rotating centrifuge basket, or pot. A suitable guide or traverse lays the thread against 70 the wall of the pot, in the form of a cylindrical cake. The thread entering the pot is twisted by the rotation of the pot. When the desired quantity of thread has been collected, the pot is removed from the spinning machine, the thread reeled up in the form of a skein and given the necessary chemical and mechanical treatments to obtain the finished product. This method is 75 superior to the first method given above, 80 but the thread is still liable to receive mechanical damage through handling the relatively weak thread in skein form during the intermediate treatments.

Broadly stated, my invention consists of 85 winding the twisted strand, composed of a plurality of spun threads, upon any suitable support, where it may be maintained under such slight tension, as will prevent it from tangling, and to subject the silk to all subsequent operations, such as those necessary to remove the copper; washing and drying, while it is still mounted upon said support. By this method the mechanical damage 90 arising from the handling of the silk in 95 skein form is completely eliminated.

More specifically my invention resides in taking the twisted strand (composed of a plurality of threads twisted together) directly from the pot of the centrifuge, and 100 winding it upon a cylinder, spool or bobbin and subjecting it to a chemical treatment to "decopp" the same, i. e. to remove the residual copper, during such winding operation. This gives the strand a uniform 105 chemical treatment and eliminates many of the defects which are found in threads which do not receive a uniform chemical treatment.

The cylinders, spools, bobbins and the 110

like are of such a nature that they may be freely moved from the decopping station to a washing station and later to a drying station so that the thread may be both 5 washed and dried while still wound upon the support. In other words, the silk is brought from the point of spinning to the point of final drying on the same support upon which it is initially wound, so that it 10 does not have to be touched by human hands and is maintained in such form that it can not become tangled, throughout its progress.

I do not limit myself as to the exact 15 form of the spool or cylinder on which the thread is wound. The spool may be slightly tapered, i. e. of a conical shape and may or may not have flanges on one or both ends. Nor do I limit myself to the method 20 of giving the thread the treatment or to the type of treatment. The cylinder may rotate about a horizontal axis, and may be partially submerged in the liquid bath used for the treatment, or the liquid may be applied by spraying it on the spool, or by 25 flowing it on by a suitable device.

One form in which the decopping apparatus may be embodied is illustrated in the single figure of the accompanying drawing. This figure is a view partly in side 30 elevation and partly in section of a simple form of apparatus for simultaneously winding the strand upon a cylinder and subjecting it to a bath for removing the copper, during such winding action. In the 35 drawing, 5 designates the pot of a centrifuge in which a plurality of parallel threads have been twisted into strand formation as indicated at 6. The strand 7 is led from the cake, deposited in the pot; 40 through a support 8 and to and through a pig tail guide 9 carried by the lower end of a traverse arm 10. This traverse arm is pivoted at 11 and is moved in one direction by a link 12 and a swinging arm 13 and in 45 the other direction by a spring 14. The arm 13 is moved against the tension of the spring by the action of a pin 15 upon a rotative worm wheel 16. The worm wheel 16 is mounted upon a drive shaft 17 and 50 imparts motion to a worm 18 and shaft 19. The shaft 19 carries a mandrel 20 upon which a cylinder 21 may be slipped, said cylinder being of such size as to frictionally engage the mandrel 20 and rotate therewith. The action of the traverse arm in 55 conjunction with the rotation of the mandrel and cylinder, causes the strand to be deposited upon the cylinder in an open and porous mass. A bath of liquid indicated 60 at 22 is so disposed with respect to the mandrel and cylinder that the lower portion of the cylinder and the strands wound thereon rotate in the bath. Each successive layer of strands is directly exposed to 65 the action of the liquid 22 and the strands

are wound up in open and porous formation to permit the liquid to find ready passage to all parts of the mass throughout the winding of strands upon said cylinder.

It is to be understood that I do not claim 70 as my invention the particular liquid employed for the removal of the copper. Dilute sulphuric acid is commonly employed for this purpose. It is common practice to remove the copper from the silk by 75 the action of this chemical. The invention resides more particularly in the manner and time of applying the liquid to the artificial silk for the removal of residual chemicals left from the preparation 80 of the solution from which the threads are formed. The chemical that it is particularly desired to remove in the copper ammonia process is the residual copper, but it is manifest that the method is of utility 85 in connection with either the viscose or the nitro processes. In the viscose process, it becomes necessary to remove residual sulphur compounds while in the nitro process it is necessary to denitrify the nitrocellulose filaments. 90

The cylinders 21 may be formed of any suitable material. I have found bakelite suitable for this purpose. After the strands are wound upon the cylinders, said cylinders 95 constitute supports or carriers upon which the strands remain under light tension during the subsequent operations of washing and drying. These cylinders may be conducted to suitable washing apparatus where they are sprayed with clear water and then be placed in drying ovens of conventional form and dried. After being dried the silk may be drawn directly from the cylinders 100 to the swifts of a skeining machine. 105

From the foregoing description it will be seen that under this invention the strands are taken directly from the spinning machine and placed upon supports under light tension and are maintained in that condition and upon said supports throughout the operations of decopping, washing, drying and skeining to bring them into their completed commercial form. The result of this is that it has been found in actual practice that practically all of the flaws and imperfections heretofore met with in the production of artificial silk are eliminated and a high grade silk is had at a minimum cost, because the usual waste and loss resulting 110 from tangled skeins and the like, is avoided. 115

Having described my invention what I claim is:

1. The herein described method of manufacturing artificial silk which consists of winding the strands of spun and twisted threads, directly from the centrifuge pot, after the latter has been removed from a spinning machine, upon a freely removable cylinder, while rotating the latter in the 120 125 130

presence of a bath adapted to chemically treat the strands, and thereafter carrying said cylinder bodily and with the strands under light tension thereon, through washing and drying steps.

2. The herein described method of manufacturing artificial silk which consists of winding the strands of spun and twisted threads, directly from the centrifuge pot, after the latter has been removed from a

water and heat proof cylinder, while rotating the latter in the presence of a bath adapted to chemically treat the strands, and thereafter carrying said cylinder bodily and with the strands under light tension thereon, through washing and drying steps, the latter steps being at elevated temperature.

In testimony whereof he affixes his signature.

CHARLES C. JESSEN.
